UNITED STATES PATENT OFFICE.

RICHARD H. WELLES, OF KENOSHA, WISCONSIN, ASSIGNOR TO THE BADGER BRASS MANUFACTURING COMPANY, OF KENOSHA, WISCONSIN, A CORPORATION OF WISCONSIN.

DESIGN FOR A HEADLIGHT.

41,052.

Specification for Design.

Patented Dec. 20, 1910.

Application filed May 4, 1910. Serial No. 559,418. Term of patent 7 years.

To all whom it may concern:

Be it known that I, RICHARD H. WELLES, a citizen of the United States, residing in the city of Kenosha, county of Kenosha, and State of Wisconsin, have invented a new, original, and ornamental Design for Headlights, of which the following is a specification, reference being had to the accompanying drawings, forming a part thereof.

In the drawings, Figure 1 is a rear end elevation of my new design and Fig. 2 is a side elevation of the same.

The lamp may be briefly described as follows: A short cylindrical barrel or main body portion 1 terminates at its rear end in a reduced convex end closure portion 2 and

at its front end in a flaring extension 3. This flaring extension 3 curves smoothly and uniformly outwardly and to it is connected a relatively narrow door 4. Upon the top of the main body portion is secured a top ventilator 5 consisting of an exteriorly convex hood 6 and a pair of lateral extensions 7. The latter are of peculiar and novel configuration as shown clearly in Fig. 2.

I claim:

The ornamental design for a headlight as shown and described.

RICHARD H. WELLES.
